ATTORNEY

UNITED STATES PATENT OFFICE.

GEORGE STUMP, OF INDEPENDENCE, KANSAS.

MACHINE FOR MAKING AND LAYING CONCRETE PIPE.

1,058,642.

Specification of Letters Patent.

Patented Apr. 8, 1913.

Application filed December 9, 1911. Serial No. 664,811.

To all whom it may concern:

Be it known that I, GEORGE STUMP, a citizen of the United States, residing at Independence, in the county of Montgomery and 5 State of Kansas, have invented certain new and useful Improvements in Machines for Making and Laying Concrete Pipe; and I do declare the following to be a full, clear, and exact description of the invention, such 10 as will enable others skilled in the art to which it appertains to make and use the same, reference being had to the accompanying drawings, and to the letters and figures of reference marked thereon, which form a 15 part of this specification.

My invention relates to apparatus for making and laying concrete pipe in trenches, and more particularly to an apparatus for making and laying continuous pipe for irrigation purposes.

The object of the invention is to provide a hand-power machine for the purpose that shall be simple and light in construction, and efficient in operation. In accomplishing this object, I have provided the improved details of structure, which will presently be fully described and pointed out in the claim, reference being had to the accompanying drawings, in which:

30 Figure I is a side elevation partly in section of a machine embodying the invention. Fig. II is a plan view thereof. Fig. III is a detail view partly in section on line *a—a* of Fig. V, omitting the oil box. Fig. 35 IV is a detail view of one of the shaft bearings. Fig. V is a detail view of a part of the gearing.

Referring more in detail to the parts:— the frame of the machine is designed for 40 use in a narrow trench, and comprises a pair of horizontal runners 1, two upright members 2, and a pair of inclined braces or stays 3, connecting the top of the former with the forward end of the latter. These parts I 45 prefer to make of light flat metal bars.

Attached to the frame parts 2 by straps 4 is the receiving chute 5 for the previously mixed material. Said chute is curved rearwardly at its lower end and connects with a 50 forming tube 6; the bore of which is that of the size pipe to be formed. The bottom of this tube is at substantially the level of the bottoms of the runners 1, which at their forward ends rest upon the ground. The 55 forward end of the frame is supported by a single centrally disposed carrying-wheel, 7.

A shaft 8 is axially disposed in the forming tube 6 and is passed through a bearing 9 in the connecting bend and extended to the forward end of the frame, close to the 60 wheels 7, at which point it has a bearing 10. Fixed on the opposite end of said shaft is the mandrel, 12. Mounted rotatably on shaft 8 is a tubular shaft 14 that extends from the mandrel 12 to a point shown on 65 Fig. I. Fixedly mounted on this shaft is the feeding or forcing worm 15. Abutting the end of the worm shaft 14 is a bevel gear wheel 16, loose on shaft 8. The hub of this wheel is drivingly connected with the worm 70 shaft 14 as shown at 17 in Fig. V. Keyed on shaft 8, facing gear 16, is a bevel gear wheel 18, and a drive pinion 19 meshes constantly with both. Pinion 19 is on a vertical shaft 20 which has bearings in suitable 75 castings 21, and has on its upper end a bevel gear wheel 22, meshing with a bevel gear wheel 23 on a transverse shaft 24, on which is a hand crank 25.

In Fig. V, 26 designates an oil box in 80 which the gears 16, 18 may run, they in turn lubricating the teeth of pinion 19. The upper ends of frame pieces 3 are connected by a handle 27, by which the machine may be lowered into a trench and raised therefrom. Supposing the machine to be positioned in a trench, one man feeds the mixed and wetted material into the chute 5. The other operator straddles the trench and turns the crank 25, steadyng the machine 85 by its handle 27. The tubular shaft 14 will be driven in one direction, causing the worm 15 to force the material out around the mandrel 12. The shaft 8 being driven in the opposite direction to that of the worm shaft, 90 the mandrel itself will be rotated thereby, and thereby neutralize any twisting effect the worm might otherwise have on the pipe. As the pipe emerges from the tube the reaction by the worm 15 thereon drives the 100 whole apparatus forward, the ends of the runners 1 sliding along the trench's bottom. It is obvious that the operation will be continuous as long as the machine is kept supplied with material and the driving crank 105 operated.

Having thus described my invention, what I claim as new therein and desire to secure by Letters-Patent is:—

In a machine of the type described, a 110 frame comprising uprights and runners, a forming tube having an upturned receiving

end attached to said uprights, a tubular shaft journaled on said tube and having a worm on its inclosed portion, a mandrel shaft extending through the tubular shaft 5 and projecting from the inclosed end thereof, a mandrel on the projecting end of the mandrel shaft, gears on said shafts, a vertical shaft mounted in the uprights, gears on the vertical shaft engaging the gears on 10 the tubular and mandrel shafts whereby the

last named shafts are revolved in opposite direction when the vertical shaft is revolved, and means for actuating the vertical shaft.

In testimony whereof I affix my signature in presence of two witnesses.

GEORGE STUMP.
